(57) **CLAIM**

I claim the ornamental design for an expansion filler module, as shown and described.

DESCRIPTION

FIG. 1 is a side plan view of the expansion filler module; FIG. 2 is an end view of the expansion filler module; and, FIG. 3 is a cross section view taken from line 3-3 of FIG. 2. The broken line showing is included for the purpose of illustrating portions of the article and forms no part of the claimed design.

1 Claim, 3 Drawing Sheets

FIG. 1

FIG. 2

FIG. 3
